UNITED STATES PATENT OFFICE.

GEORGE C. HARLIN, OF HEDRICK, IOWA.

GEARING FOR WASHING-MACHINES.

SPECIFICATION forming part of Letters Patent No. 367,039, dated July 26, 1887.

Application filed July 21, 1886. Serial No. 208,657. (No model.)

To all whom it may concern:

Be it known that I, GEORGE C. HARLIN, a citizen of the United States of America, residing at Hedrick, in the county of Keokuk 5 and State of Iowa, have invented certain new and useful Improvements in Gearing for Washing-Machines, of which the following is a specification, reference being had therein to the accompanying drawings.

10 This invention pertains to certain new and useful improvements in gearing for washing-machines; and it consists in the construction, combination, and arrangement of the parts, substantially as hereinafter fully set forth, and 15 particularly pointed out in the claim.

In the accompanying drawings, Figure 1 is a cross-sectional view of my invention, and Fig. 2 is a detail view thereof.

In carrying out my invention, I secure to 20 the upper outer surface of the lid or cover A of an ordinary tub or receptacle, B, a flat horizontal plate, a. From one end of said plate is an upwardly-projecting overhanging bracket, a', to the upper and lower ends of the 25 overhanging portion of which are rigidly secured or made integral therewith two oppositely-projecting cylindric sleeves or collars, a''. These sleeves or collars are apertured or hollow in their central portion, corresponding to 30 a vertical aperture or passage formed in the overhanging portion of the bracket a', the purpose of which will now appear.

C is a vertical shaft, upon the lower end of which is rigidly secured an ordinary agitator, 35 C', and this shaft is passed through an aperture or opening formed in the center of the lid or cover and the flat horizontal plate a, and up through the sleeves or collars and the overhanging portion of the bracket a'. This 40 shaft has rigidly secured thereto, between the flat horizontal plate a and the lower sleeve or collar, a small pinion, b, and a similar pinion, b', on the extreme upper end thereof, the same resting on the upper outer end of the upper 45 sleeve or collar. These pinions b b' are designed to be alternately engaged by a semi-cogless wheel, D, secured upon the outer end

of a shaft, D', the extreme end of said shaft resting in a small opening or aperture formed in the front surface of the overhanging portion of the bracket a'. This shaft is also supported near its outer end in a shaft-bearing or standard, d, integral with the flat horizontal plate a, and said shaft has an ordinary crank-handle, d', secured to its outer end. A small 50 collar, d'', having a set-screw, d'', is secured on the shaft D', immediately adjacent the shaft bearing or standard d, to regulate the adjustment of said shaft.

From what has been said it will be seen that 55 by turning the crank-handle the cogged portion of the wheel D will be caused to gear alternately with the pinions b b', thus causing the movement of the vertical shaft and its agitator first in one direction and then in another. 60

I am aware that it is not new to provide a washing-machine with two oppositely-disposed semi-cogless wheels alternately gearing with a single pinion on the agitator-shaft; but my invention is designed as an improvement 65 over such a device, and by employing but one semi-cogless wheel and two pinions on the agitator shaft I greatly reduce the weight of the mechanism necessary to the accomplishment of the desired result, and the device is 70 not as liable to get out of order, owing to the few number of parts employed, as is a machine 75 of the construction above outlined.

Having thus fully described my invention, what I claim, and desire to secure by Letters 80 Patent, is—

The combination of the bracket having the sleeves or collars, the vertical shaft, the pinions secured thereon, the semi-cogless wheel, and the horizontal shaft having its end resting 85 in said bracket, all arranged substantially as shown and described.

In testimony whereof I affix my signature in presence of two witnesses.

GEORGE C. HARLIN.
